RADIO TELEGRAPH SYSTEM

Lawrence E. Schmitt, Park Ridge, Ill., assignor to
Teletype Corporation, Chicago, Ill., a corpora-
tion of Delaware

Application June 13, 1932, Serial No. 616,946

2 Claims. (Cl. 250—8)

This invention relates broadly to radio telegraph systems and more particularly to a system at a receiving station for the reception of radio telegraph signals.

One of the objects of the present invention is to provide a system with neutralizing means associated with receiving and amplifying apparatus at a receiving station whereby possible objectional disturbances may be neutralized without impairing the normal telegraphic signals.

Another object of the invention is to provide a relay system at a receiving station suitable for translating incoming radio signals into local electric current signals to operate a printing telegraph receiver, and to prevent parasitic signals such as static from disturbing the normal operation of the printing telegraph apparatus.

These objects are attained by providing a receiving, detecting and amplifying system of any well known or desired design and adding thereto an auxiliary system for amplifying and neutralizing static signals, the auxiliary system being such that it is ineffective upon normal telegraphic signals and therefore does not neutralize those signals.

The invention of the present application constitutes an improvement upon the system of my U. S. Patent 1,705,211 issued March 12, 1928 and for a further understanding of the invention reference is made to that patent.

The invention will be clearly understood by reference to the accompanying specification and drawing in which

Fig. 1 shows a transmitting station for intermittent single frequency radio transmission, and

Fig. 2 shows the circuit of a receiving station adapted to operate under control of the sending station of Fig. 1.

In the figures the transmitting station is adapted to send a continuous radio-frequency current as a marking signal and to interrupt that current as a spacing signal. The receiving station has a differential relay whose first winding receives in amplified form the signals sent by the transmitting station and whose second winding receives neutralizing currents through an auxiliary system containing an electronic valve. In operation with a polar relay, the second winding of the relay may be the local biasing winding. To prevent the telegraphic signals from reaching the neutralizing winding through the electronic valve, the auxiliary system containing the second winding is detuned from the frequency of the current of the received signal.

Referring to Fig. 1, a transmitting antenna 1 is

grounded at 2 through a winding 3 which is associated with an oscillator formed by the parallel connection of electronic tubes 4 and 5. The oscillator circuit is formed by connecting the input and output circuits of electronic tubes 4 and 5 through the transmitting inductance 8. The cathodes of tubes 4 and 5 are supplied from a battery 6 while the plate potential for the oscillator is supplied from a generator 7. The arrangement of the transmitter may be any form desired since the invention pertains more specifically to the receiving apparatus. Connected in shunt of the transmitting inductance 3 and acting to ground the antenna 1 are the contacts of the transmitting relay 9. For printing telegraph transmission the transmitting circuit comprises the transmitting relay 9 and an automatic transmitter having a plurality of contacts 10, one of which is normally closed as is customary in printing telegraph operation. The contacts 10 have a normal stop contact and five signal contacts for successive operation and may be operated by a tape transmitter or manual keyboard transmitter as desired.

Referring to Fig. 2 the receiving station is similar to Fig. 2 in the Patent 1,705,211 above identified and has the added shunt comprising rheostat 12 and inductance 13. The receiving station comprises an antenna 14 connected through a tuner 15 to ground, which may be of any desired form. The received energy is amplified by the amplifier indicated at 16 and a local frequency is generated by the heterodyne indicated at 17 connected to the amplifier 15 for heterodyning the incoming signal. The output of the receiving apparatus thus far described is carried by conductors 18 to the input circuit of a relay system designated generally by reference character 19. The relay system 19 includes an audio frequency iron core input transformer 20 designed for high efficiency at the audio-note employed in the marking signals. The primary winding 21 provides energy for two secondary windings 22 and 23 which are tuned respectively by variable condensers 24 and 25. Filter circuits 26 and 27 are inserted in the secondary circuits to increase the sharpness of tuning. Electronic tubes 32 and 33 receive the signal impulses on their respective grids 34 and 35. A negative bias is maintained on these grids by a C-battery 36. The plate circuit of tube 32 connects plate 37 through a local winding 38 of a polar relay 39 and one winding 40 of a differential milliammeter 41 to the positive terminal of B-battery 42. The plate circuit of the tube 33 connects the plate 43 through a

line winding 44 of the polar relay 39 and through a winding 45 of the milliammeter 41 to the battery 42. Filament rheostats 46 and 47 regulate the temperature of cathodes 48 and 49 respectively, the filaments being heated by current from an A-battery 54. The windings 38 and 44 of polar relay 39 operate the armature 50 which closes at all times one or the other of two contacts 51 and 52. Should a printer 55 be neutral to polarity, its armature having a return spring, then the spacing contact 52 may be left unconnected as shown and the marking contact 51 may be provided with a battery of either polarity. Should the printer 55 be of polar nature, batteries of two polarities are provided upon the contacts 51 and 52.

Current from battery 42 through the biasing winding 38 of the polarized relay 39 is capable of adjustment by means of resistance 12 which is included in circuit with an inductance 13. The inductance 13 functions as a choke coil to prevent the introduction of extraneous currents in the output circuit of the vacuum tube 32. Through adjustment of resistance 12, the value of the biasing current on winding 38 may be varied to suit particular conditions.

In adjusting the relay system 18 for operation in response to signals received from the transmitter disclosed in Fig. 1, test keys 51 and 58 are opened, and that circuit path of the relay system which includes the transformer secondary winding 22, condenser 24, vacuum tube 32, and winding 38 is tuned, by adjusting the condenser 24, to produce a maximum or desired deflection in the milliammeter 41. The purpose of first tuning and then detuning the circuit is to place it in a condition very near the resonance with the frequency of the predetermined single audio-frequency current, but substantially completely out of resonance with such frequency, so that little or no current of the frequency of the signal will flow in the circuit. Key 58 is then closed and the other circuit path of the relay system, which includes the transformer secondary winding 23, condenser 25, vacuum tube 33, key 58, and the winding 44, is tuned by adjusting the condenser 25, to its point of resonance with the predetermined single audio-frequency signal or to produce a maximum or desired deflection of the milliammeter 41. Of course, the above described conditions are established subsequent to the adjustment of the biasing effect resulting from the C battery 36, as is well understood in the operation of circuits of the character disclosed in the drawing. After noting the deflection of the milliammeter 41 in response to the adjustment of condenser 25, key 57 is closed and rheostat 12 is adjusted to reduce the deflection of the milliammeter 41 to one-half of the value previously indicated thereon through the adjustment of condenser 25. The current flowing through winding 38 of polarized relay 39 is now sufficient to maintain armature 50 in contact with contact 51, when signals are not being impressed on the antenna 11 in response to the operation of the transmitter disclosed in Fig. 1. However, when signals are received on the primary winding 21 of the transformer 29, Fig. 2, vacuum tube 33, having its input circuit tuned to such frequency, responds accordingly, and current flows in its output circuit, energizing winding 44 of the polarized relay 39. The effect of current through winding 44 is sufficient to counteract or overcome the action of current through winding 38 of the polarized relay 39 and thus move its armature 50

from engagement with contact 51 into engagement with contact 52, causing the corresponding operation of the printer 55.

The operation of the system is as follows:

A continuous signal radiated from the antenna 11 is received by the antenna 11 and results in a continuous current through the winding 44 of the relay 39 which controls the armature 50 in the position shown. The current through the winding 44 is opposed by a current of half the volume and in the opposite direction through the winding 38 which is produced in the winding 38 by the rheostat 12 and the battery 42. There is no current through the tube 32 during the period of normal signaling. Upon cessation of the signal by opening the contacts 10 to permit the relay 9 to shunt the winding 3, the current through winding 44 ceases and the current through winding 38 controls the armature 50 to move to its opposite position. To this change in position of armature 50 the printer 55 responds. Alternating periods of current and no-current upon the antenna 11 and in the winding 44 result in the proper operation of the printer 55 to record the received message.

The system including winding 22, condenser 24 and electronic valve 32 does not furnish any current at any time in normal operation because it is tuned out of the frequency which operates electronic tube 33 but is tuned so near to that frequency that it is out of any other frequency in use by any other system at that time.

Should a static disturbance produce effects on the antenna 11 and therefore in the primary winding 21 the effects will be transferred to both 35 of the windings 22 and 23 and will effect both of the electronic valves 32 and 33 to produce simultaneous but opposite magnetic effects in the polar relay 39 thus producing no effect upon the armature of that relay and producing no effect 40 in the printer 55. This is the neutralizing condition for which the elements 22 and 32 are present in the structure.

Although the invention has been described in connection with a specific form thereof it will 45 be understood that it has further applications and it is not intended to be limited in scope by the embodiment shown herein for illustration.

The invention claimed is:

1. In a receiving system for single-frequency 50 radiant-energy telegraph systems, an antenna, an audio-frequency transformer, a first local circuit associated with said antenna through said audio-frequency transformer and tuned to the audio-frequency of the heterodyned signal and 55 subject to both signal currents and static disturbance upon said antenna, a first key to open said first circuit, a second local circuit similarly associated with said antenna and detuned from the said audio-frequency and subject to static 60 disturbance only upon said antenna, a biased polar relay, an operating winding and a biasing winding for said relay, said relay having said first circuit connected with its operating winding and said second circuit connected with its biasing 65 winding, a biasing circuit connected as a derived circuit upon said second circuit, a second key to open said biasing circuit, and a printing telegraph recorder controlled by the contacts of said polar relay.

2. In a receiving circuit for single frequency 70 radio telegraph signals, a detector circuit having two paths, one tuned to a predetermined single audio-frequency of a heterodyned signal and subject also to currents generated by static disturb- 75

ances, and the other path detuned to said pre-determined single audio-frequency but subject to currents generated by static disturbances, a polarized relay connected to said two paths having an operating and a biasing winding, with the operating winding responsive to currents of the pre-determined single audio-frequency current and the biasing winding non-responsive thereto, means connected in circuit with said biasing 5 means connected in circuit with said biasing 10 winding and the path which is detuned to the pre-

determined single audio-frequency to determine the degree of bias on said biasing winding, circuit interrupting means local to the detector and included in the respective paths for rendering said respective paths effective or non-effective on the windings of said polarized relay, and a recorder controlled by said polarized relay in its response to current through the path tuned to said audio-frequency current.
